UNITED STATES PATENT OFFICE.

MATHIAS DEZURIK, OF SARTELL, MINNESOTA.

PULP-FIBER-CLEANSING APPARATUS.

Application filed November 10, 1924. Serial No. 749,000.

This invention relates to improvements in pulp fiber cleansing processes and apparatus particularly adapted for use in cleansing pulp fibers preparatory to being made or converted into new paper stock, and more particularly relates to such a process and apparatus adapted for use to cleanse and separate pulp fibers, made from old newspapers, magazines, books, etc., from the impurities 10 contained therein, particularly printer's ink, sizing, etc.

In the manufacture of new paper stock, it is desirable from an economical stand-point, to use old newspapers, magazines, books, and 15 the like, and the above material, after having been disintegrated and reduced, in the usual manner, to a fibrous pulpy mass of a liquid consistency, must be passed through a separating and cleansing process for the purpose 20 of separating therefrom, all such impurities as printer's ink, sizing, etc., and for the purpose of thoroughly cleansing the finely divided stock or pulp fibers.

The particular object of this invention, 25 therefore, is to provide an improved process and apparatus for removing from pulp fibers, ink and other impurities, and also for cleansing such fibers preparatory to being converted or manufactured into new paper 30 stock.

Other objects of the invention will appear from the following description and the accompanying drawings and will be pointed out in the annexed claims.

In the drawings there has been disclosed a 35 structure designed to carry out the various objects of the invention but it is to be understood that the invention is not confined to the exact features shown, as various changes 40 may be made within the scope of the claims which follow.

In the drawings:

Figure 1 is a vertical-sectional view on the line 1—1 of Figure 2, showing the general 45 construction of the improved apparatus;

Figure 2 is a front view of the apparatus shown in Figure 1;

Figure 3 is a detail sectional view on the line 3—3 of Figure 1, showing the spout or 50 trough into which the waste water and impurities are discharged;

Figure 4 is a similar view on the line 4—4 of Figure 1;

Figure 5 is a sectional view on the line

5—5 of Figure 1, showing the trough into 55 which the cleaned pulp fibers are discharged;

Figure 6 is an enlarged detail sectional view on the line 6—6 of Figure 2, showing one of the mixing troughs wherein the partially cleaned pulpy mass is discharged from 60 the separating screens and thoroughly mixed with water before being discharged to the next separating screen.

Briefly, the invention consists in progressively and gravitationally passing the unclean pulp fibers, in a watery state, over the surface of a series of inclined separating screens, and alternately adding and draining a cleansing water therefrom until substantially all of the impurities have been removed, after which the cleaned fibers are discharged into a receiving means adjacent the lower portion of the apparatus for subsequent use in the manufacture of new paper stock.

The novel pulp fiber cleansing apparatus shown in the accompanying drawings preferably comprises a box like base structure having a series of inclined separating screens 7, 8 and 9 arranged one above the other as shown in Figure 1. These screens are suitably mounted between and secured to the opposed members 11 and 12 which are supported by upright supporting members 13, preferably mounted upon the beams 14 as shown in Figures 1 and 2. The lower ends of the side members 11 and 12 are also preferably supported upon the beams 14 as shown.

A suitable receiving means or trough 15 is provided adjacent the upper edge of the screen 7. Into this trough the uncleaned pulp fiber is discharged in a watery state from a distributing pipe 16 having a plurality of spaced discharge pipes 17 connected thereto and adapted to downwardly direct 90 the watery pulp fiber into the trough 15. A feed pipe 18, having a control valve 19, mounted therein, is connected to one end of the distributing pipe 16 and leads therefrom to a suitable source, not shown. As the unclean pulp fiber is discharged into the trough 15, it will overflow the relatively lower wall 21 thereof and will be discharged onto the screen 7 over the surface of which it will 95 downwardly travel by gravity. From the screen 7 the partially cleaned fibers will be discharged into a mixing box or trough 22. Means are preferably provided for evenly

distributing the pulp fiber over the surface of the screen 7. Such means preferably consists in the provision of a member or splash board 23, having its ends secured to the end members 11 and which board is arranged in spaced relation to the wall 21 of the trough 15 and also to the bottom wall 24 of the trough 15. This splash board functions to prevent the watery pulp mass discharged 10 into the trough 15 from splashing over the wall 21 to the surface of the screen. The space provided between the wall 21 and the lower portion of the splash-board 23 is of such size as to cause the material to be evenly 15 distributed over the surface adjacent the screen, thereby eliminating any danger of the material being unevenly discharged to the surface of the adjacent screen which will interfere with the cleansing and separating process. As the material downwardly travels 20 over the surface of the screen 7, a portion of the water contained therein will drain through the screen and will be discharged to the inclined bottom wall 25 of the apparatus, 25 removing with it a portion of the impurities, while the partially cleaned fibers will be discharged into the mixing trough 22.

In order that substantially all of the impurities may be removed from the pulp fiber 30 it is necessary that means be provided whereby a cleansing water may be added thereto and the partially cleaned fibers thoroughly mixed therewith so that when the pulp is discharged from one screen to the next, a 35 similar cleansing process will take place. Such a means is shown in the drawings, particularly Figures 1, 2, 3 and 6. As here shown, a pipe 26, having a series of discharge nozzles 27 mounted therein, is arranged directly above each mixing trough 22 and each pipe 26 has one end connected to a feed pipe 28 whereby water may be supplied thereto. Suitable valves 29 are interposed in each pipe 26 whereby the supply of 45 water to the mixing troughs 22 may be regulated. The form of apparatus shown in the drawings comprises three screens having the mixing troughs 22 arranged therebetween as particularly shown in Figure 1. Each mixing trough preferably comprises an inclined wall 31 to which the lower edges of the screens 7 and 8 are secured by means of suitable cleats 32, and a bottom wall 33 to which the adjacent lower screen is similarly secured by 55 means of the cleats 34. The discharge side of each trough 22 preferably consists of an overflow wall 35 over which the watery pulp fibers are discharged onto the bottom wall 33 and thence through a relatively narrow 60 opening or gap 36 provided beneath the splash-board 37. Similarly, the splash-board 37 is arranged comparatively close to the overflow wall 35 of the mixing trough so that as the material downwardly flows between the two walls it will be evenly distrib-

uted over the surface of the adjacent lower screen. The form of nozzle 27 shown in the accompanying drawings is preferably of the type shown in the prior application of the inventor hereof, filed August 7, 1924, Serial 70 No. 720,748, which has eventuated in Patent No. 1,617,673, dated February 15, 1927. This type of nozzle is provided with a narrow elongated discharge opening so that the water discharged therefrom will be spread in the 75 form of a sheet, as indicated by the dotted lines in Figure 3, so that the partially cleaned pulp fibers discharged into the mixing troughs 22 from the screens 7 and 8 will be thoroughly mixed with the cleansing water 80 as it is discharged under pressure thereinto. The unclean water and impurities, separated from the pulp through the screens 7 and 8 and discharged to the inclined bottom 25 of the apparatus, is preferably discharged 85 into a transverse spout 38, as waste, and may be discharged therefrom into a sewer or other receiving means.

From the lower mixing box 22, the pulp fibers will be discharged to the lower screen 9 and, as it downwardly travels over the surface thereof, the major portion of the water contained therein will drain through the screen and be discharged to the lower inclined wall 39 arranged beneath the screen and from which it is discharged into a spout 41. The water passing through the screen 9 will be comparatively clean and may therefore be used over again. From the lower screen 9, the cleaned fibers will be discharged into a receiving spout or trough 42 from whence it will be discharged into a suitable receiving means, not shown, for subsequent use in the manufacture of new paper stock.

A platform 43 is preferably arranged adjacent each screen 7, 8 and 9 and a stairway 44 is preferably provided between each platform so that an attendant may conveniently reach any one of the screens, should it be found necessary to clean them or in the case of 105 repairs, and the like. The distributing pipe 16 is preferably connected to the water feed pipe 28 by means of a pipe connection 45, having a control valve 46 therein, so that should the pulp not have sufficient moisture to cause it to freely flow over the wall 21 of the receiving box 15, additional water may be added thereto by opening the valve 46.

In the operation of this novel apparatus, the pulp fiber is discharged, in a watery state, 120 into the receiving box or trough 15 adjacent the upper edge of the screen 7. From this trough it will overflow the wall 21 and pass between the narrow opening provided between the wall 21 and the splash-board 23, 125 thence to the upper screen 7. As it downwardly travels over the surface of this screen a portion of the water contained therein will drain through the screen thereby carrying with it a portion of the impurities contained 130

in the pulp. The screens are arranged at such an incline as to cause the material to travel downwardly over the surface of the screen as the water is drained therefrom, thereby being discharged into the first mixing trough 22 in a thick pulpy mass. While the drained material is thus temporarily arrested by this first trough, water is added under pressure to the thickened mass, thereby thoroughly mixing it with water and also agitating it until the pulp fibers are substantially separated from one another and liquefied to the extent that they will freely overflow the wall 35 of the mixing trough and pass downwardly between this wall and the splash-board 37 adjacent the lower screen 8 to resume their downward travel. The same process of separating and removing impurities from the fibers will take place on the screen 8 so that by the time the pulp reaches the lower mixing trough 22 it will be comparatively clean due to this alternate draining and adding of water. It will then again be thoroughly mixed with water and agitated in 25 the lower mixing trough and will thereafter be discharged to the lower screen 9 where the water will again be drained from it and will be discharged into the lower receiving spout 42 in a substantially clean state. As hereinbefore stated, the water passing through the screens 7 and 8 will remove substantially all of the impurities from the pulp and will therefore be discharged as waste into the spout 38. The water passing through the screen 9 will be comparatively clean and may therefore be used again in preparing other pulp for a similar cleansing and separating process.

In the drawings, there is shown a structure 40 comprising three separating screens and two mixing troughs but it is to be understood that any number of such screens and mixing troughs may be used without departing from the invention.

Having thus described my invention what I claim as new and desire to secure by Letters-Patent, is:

1. A pulp fiber cleansing apparatus comprising a box-like structure having side walls 50 and an inclined bottom, a series of successive inclined screens arranged within the box-like structure and spaced above its inclined bottom, a transversely extending raw stock-receiving trough positioned at the upper end 55 of the box-like structure and formed with an overflow wall and a splash-board positioned to form a space between it and the overflow wall for the passage of stock flowing from the trough, an opening being formed beneath the 60 splash-board for delivery of the stock onto the uppermost screen, and the successive lower screens having the lower end of one screen connected to the upper end of the next screen by a transversely extending stock-receiving trough formed with an overflow wall 65

for the flow of stock from the lower end of one screen onto the upper end of the next screen, a splash-board spaced from the overflow wall of the trough and disposed to leave a space between the wall and board for the 70 flow of stock onto the next lower screen through an opening at the lower end of the splash-board, and means for supplying water to the stock in each trough, the head of the screen receiving stock from the trough being 75 at a higher level than the discharge end of the preceding screen, and the water drained from the stock passing over each screen being discharged onto the inclined bottom of the box-like structure, the inclined bottom of 80 the box-like structure extending beneath all the sieves to receive the drainage directly therefrom and the opening beneath the mentioned splash-boards being above the plane of the receiving ends of the sieves and the 85 plane of the preceding sieve for even distribution of the stock across the surface of the receiving sieve.

2. A pulp fiber cleansing apparatus comprising a box-like structure having side walls 90 and an inclined bottom, a series of successive inclined screens arranged within the box-like structure and spaced above its inclined bottom, a transversely extending raw stock receiving trough positioned at the upper end 95 of the box-like structure, and transversely extending troughs connecting the discharge end of one screen with the head of the next succeeding screen, each of the several troughs having an overflow wall and a bottom projected beyond the overflow wall, a splash-board spaced from the overflow-wall of each trough and terminating to form an opening between its lower end and projecting portion of the trough bottom for the travel of 100 the overflow-stock from the trough onto the head of the next succeeding screen, and means for supplying water to the stock in each trough.

3. A pulp fiber cleansing apparatus comprising a box-like structure having side walls and an inclined bottom, a series of successive inclined screens arranged within the box-like structure and spaced above its inclined bottom, a transversely extending raw stock receiving trough positioned at the upper end of the box-like structure formed with an overflow wall and a splash-board positioned to form a space between it and the overflow wall for the travel of stock overflowing from 110 the trough, an opening being formed beneath the splash-board for delivery of stock onto the uppermost screen, transversely extending troughs connecting the discharge end of one screen with the head of the next succeeding screen, each of said troughs being formed with an overflow-wall and with an inclined wall to which wall the discharge end of the preceding screen is coplanar, a splash-board 115 spaced from the overflow-wall of each of said 120

125

130

troughs and terminating to form an opening for the travel of the overflow stock from the trough onto the head of the next succeeding screen, and means for supplying water to the stock in each trough.

4. A pulp fiber cleansing apparatus comprising a box-like structure having side walls and an inclined bottom, a series of successive inclined screens arranged within the box-like structure spaced above its inclined bottom, the inclined bottom extending beneath all the screens, transversely extending troughs connecting the discharge end of one screen with the head of the next succeeding screen, each of said troughs being formed with an over-

flow-wall and with a splash-board positioned to form a space between it and the overflow-wall and an opening beneath the board above the plane of the screen for the travel of stock overflowing from the trough and its delivery to the head of the next succeeding screen, and a trough disposed below the discharge end of one of the screens to intercept the drainage from the preceding screens and prevent it mingling with the drainage from the next succeeding screen.

In witness whereof, I have hereunto set my hand this 6th day of November, 1924.

MATHIAS DEZURIK.
